STONE FINISHING MACHINE

Frank Pierce, Rutland, Vt.

Application February 10, 1936, Serial No. 63,228

7 Claims. (Cl. 51—100)

This invention relates to a machine for producing a plane or formed surface on a block of granite or other stone.

It is the general object of my invention to provide an improved machine for such purposes by which a plane or formed surface of any desired contour may be easily and economically produced.

In the preferred embodiment of my invention, I provide a grinding drum movable vertically during the grinding operation and I also provide means for moving said grinding drum or the work relatively horizontally in accordance with a desired pattern. I also provide means by which the horizontal movement may be automatically controlled.

My invention further relates to arrangements and combinations of parts which will be herein-after described and more particularly pointed out in the appended claims.

A preferred form of the invention is shown in the drawings, in which

Fig. 1 is a side elevation of my improved machine;

Fig. 2 is a plan view thereof;

Fig. 3 is a rear elevation thereof;

Fig. 4 is a detail plan view, looking in the direction of the arrow 4 in Fig. 3;

Figs. 5 and 6 are enlarged side elevations of certain parts;

Fig. 7 is a detail plan view to be described, and

Figs. 8 and 9 are front and end views of a grinding drum.

Referring to the drawings, my improved stone finishing machine preferably comprises a base 10 (Fig. 1) on which a work supporting table 11 is slidably mounted. The table 11 may be moved toward and away from a grinding drum 12 by a feed screw 13 (Fig. 2) connected by bevel gears 14 and 15 to a back shaft 16 which in turn may be connected by a gear 17 and a pinion 18 to a shaft 19, which is rotated through a speed-reducing device 20 from the armature shaft 21 of a reversible motor M.

The back shaft 16 may also be directly connected by a gear 22 and pinion 23 to the armature shaft 21 to provide a high speed drive for moving the work to or away from operative position. Suitable provision is made for selectively connecting the gears 17 and 22 to the back shaft 16.

The table 11 is preferably provided with an upstanding back portion 25 (Fig. 2) and with an end portion 26 (Fig. 1) movable to accommodate longer or shorter stones, both portions 25 and 26

being formed integral with or rigidly secured to the table 11. A block of stone S is placed on the table 11, preferably resting on wood strips 27 (Fig. 1) and is so located as to be positioned by the back 25 and end portion 26.

A clamping arm 30 (Fig. 2) is pivoted at 31 on the end portion 26 and is provided with a clamping screw 32 at its outer end. The arm 30 is also provided with a lug or flange 33 normally engaging a block 34 (Fig. 4) at the end of a spring plunger 35. When the block 34 is in normal position, the arm 30 is held from angular movement and pressure may be applied to the stone S by means of the clamping screw 32 and hand wheel 36. By such application of pressure, the stone S is forced against the back 25 or against interposed wood strips 37 (Fig. 2).

When a stone is to be removed and replaced it is desirable that the arm 30 be swung out of operative position. For this purpose I provide a hand lever 40 (Fig. 4) engaging a collar 41 on the spring plunger 35. By moving the hand lever in the direction of the arrow a in Fig. 4, the block 34 may be removed from holding position so that the arm 30 is free to swing away from the stone S.

When the arm 30 is returned to operative position, the block 34 automatically resumes its normal holding position.

The grinding drum 12 (Fig. 2), previously mentioned, is mounted on one end of a grinding shaft 45 which is an extension of or coupled to the rotating element of the grinding motor M'. These several parts are supported by a grinding carriage 46 (Fig. 3) which is vertically slidable on guideways on a fixed stand or post 47 (Fig. 1).

The grinding carriage 46 is raised or lowered by a feed screw 50 (Fig. 3) having a worm gear 51 at its upper end, engaged by a worm 52 mounted on the armature shaft of a reversible motor M² secured at the top of the post 47. The post 47 is preferably of hollow construction and constitutes a casing for a heavy counterweight 53, suspended by a cable 54 which runs over a sheave 55 and has its other end connected to the grinding carriage 46.

By rotating the motor M² in one direction or the other, the carriage 46, together with the grinding drum 12 and grinding motor M', may be fed upward or downward as desired. The counterweight 53 substantially reduces the load on the motor.

The grinding action in my improved machine is effected by gravity feed of a continuous supply of steel shot or other similar abrasive to the

converging space between the upper surface of the grinding drum 12 and the upright end face of the stone. The drum 12 is commonly formed of cast iron or soft steel and may be of either 5 one-piece or disc construction and with either a straight or formed face.

As it is desirable to use the steel shot over and over, I preferably provide a conveying mechanism to return the shot to feeding position. 10 This mechanism comprises a belt 60 (Fig. 1) having a plurality of buckets 61 and running on a lower conveyor pulley 62 and an upper pulley 63. At its lower end, the conveyor extends into a well or pocket 64 in which the steel shot collects after 15 passing the grinding drum.

The bucket conveyor is enclosed by a casing 65 (Fig. 1) and at its upper end is provided with an offset portion 66 having a delivery pipe 67 through which the shot raised by the buckets is 20 delivered to a feed chute 68 which extends to the upper edge of the stone surface to be finished.

The grinding drum 12 (Fig. 5) is provided with a wheel guard or casing 70 which at its upper end supports a plate 71 which is engaged by the 25 shot fed from the trough 67 during the grinding operation, and which deflects the shot so that they fall by gravity into the converging space between the upper portion of the drum 12 and the adjacent face of the stone S.

Any suitable provision may be made for driving 30 the conveyor belt 60. In Fig. 1, I have indicated the lower pulley 62 as provided with a worm wheel 72 engaged by a worm 73 connected by bevel gears 74 and 75 to the armature shaft 76 of a conveyor motor M³.

It is sometimes desirable to give the grinding drum 12 a slow axial oscillation to uniformly distribute the wear thereon. For this purpose the grinding carriage 46 (Fig. 5) may be provided 40 with guideways 80 and the grinding drum 12, shaft 45 and grinding motor M' may be mounted in a bearing structure 82, formed separate from the carriage 46 and slideable endwise in the guide-ways 80.

A worm 83 (Fig. 7) is rotatably mounted in the 45 bearing structure 82 and is held from axial movement relative to said structure. The worm 83 may be driven from the grinding shaft 45 through any usual gear connection, as 84—84 (Fig. 7).

The worm 83 engages a worm wheel 85 mounted 50 to rotate about a bearing stud 86 on the structure 82 and having associated therewith an eccentric 87 rotatable in a circular opening in one end of an eccentric link 88. The opposite end of the 55 link 88 is pivoted on a stud 89 mounted in a bracket 90 carried by the grinding carriage 46.

As the grinding wheel shaft rotates, the worm 55 shaft 85, and eccentric 87 are also rotated, and as one end of the link 88 is fixed, the rotation 60 of these parts causes a relatively slow axial oscillation of the bearing structure 82 and its associated parts, as indicated by the double arrow b in Fig. 7.

I will now describe the mechanism by which the 65 stone S may be fed automatically toward or away from the grinding drum 12 to produce a desired contour. For this purpose I provide a flexible templet or pattern 92 (Figs. 1 and 5) having a plurality of slotted bars 93 pivotally 70 connected thereto.

At the rear of the back portion 25 I provide a 75 vertical flange 94 (Fig. 2) having a T-slot 95 to receive bolts 96 which also extend through the slots in the bars 93. By bending the flexible templet 92 and securing the bars 93 in selected

positions, the templet may be caused to assume any desired configuration and will be mounted in fixed position on the work table 11 and adjacent the surface of the stone S which is to be finished.

A follower roll 100 (Fig. 6) is mounted on an arm 101 which is pivoted at 102 to a bracket 103 adjustably mounted on a stand 104 (Fig. 1) which in turn is secured to the grinding carriage 46. A hand wheel 105 (Figs. 1 and 5) is provided for adjusting the bracket 103 on the stand 104.

The arm 101 (Fig. 6) has a circuit-closing extension 110, the outer end of which is positioned between upper and lower contact screws 111 and 112. A spring 113 tends to press the roll 100 15 against the templet 92.

The contact screws 111 and 112 are connected by wires 114 to any usual control mechanism by which the motor M may be caused to rotate in selected directions.

The operation of my automatic control mechanism is as follows:—When the parts are in the position shown in Fig. 1, the bracket 103 is adjusted by the hand wheel 105 so that the extension 110 will be in neutral position and out of engagement with either contact screw 111 or 112. As the grinding drum is moved downward, the roll 100 may presently engage a portion of the templet 92 curving to the left in Fig. 1. Such engagement will swing the arm 101 on its pivot 102 and will cause the extension 110 to engage the contact screw 112. This will cause the motor M to rotate in a direction to withdraw the stone S from the grinding drum 12 until the contact arm 101 is again in neutral position.

If on the other hand the templet 92 recedes 35 from the roll 100, the spring 113 swings the arm 110 against the contact screw 111 and the motor M is rotated to advance the stone toward the grinding drum. In this way the stone is withdrawn or advanced in accordance with the indications of the templet 92, and the configuration of the templet is reproduced in the finished surface of the stone.

It will be understood that suitable switches 45 and connections are provided for starting and stopping the motors M' and M³ and for causing the motors M and M² to rotate in selected directions. Provision is also made for supplying water to the grinding drum.

While my improved finishing machine gives 50 excellent satisfaction when provided with a plain surface drum, the cutting rate may be increased under some circumstances by providing serrations 115 (Fig. 9) in the face of a drum 116, said serrations preferably having inclined or 55 oblique following surfaces as shown in Fig. 9.

Having thus described my invention and the 60 operation thereof, it will be seen that I have provided a simple and efficient machine for automatically producing a contoured surface on a piece of granite or other stone. The grinding drum has a straight line vertical feeding movement on the fixed post 47, and the stone S has sufficient horizontal movement to advance the stone to grinding position and to duplicate the 65 contours of the pattern.

The work of removing stock from the stone is 70 very rapidly and effectively performed by the steel shot, fed by gravity into the converging recess between the drum and the stone, and the grinding drum may be flooded with shot, as the surplus shot is all promptly returned by the bucket conveyor for further use.

By the use of my improved finishing machine, 75 a contoured surface may be produced on a block

of granite or other stone more rapidly and much more economically than by any other grinding machine or stone finishing machine with which I am familiar.

5 Having thus described my invention and the advantages thereof, I do not wish to be limited to the details herein disclosed, otherwise than as set forth in the claims, but what I claim is:—

1. A stone finishing machine comprising means 10 to support a stone, a grinding drum, means to support said drum for rotation on a horizontal axis, means to move said drum vertically downward in the direction of a grinding cut, said drum engaging said stone at one side of said drum and 15 substantially at the horizontal level of its axis, means to feed loose abrasive into the converging recess between the upper surface of said drum and the stone, and means to rotate said drum so that the surface thereof adjacent said stone 20 moves downward at its point of engagement therewith.

2. A stone finishing machine comprising a grinding drum rotatable about a horizontal axis, means to feed said drum vertically in the direction of a grinding cut, a stone supporting table, 25 pattern-controlled automatic means to cause said table to horizontally approach or recede from said drum during said vertical grinding operation, means to rotate said drum so that the 30 surface thereof adjacent said stone moves downward, and means to feed loose abrasive to said stone above said grinding drum.

3. A stone finishing machine having, in combination, a work supporting table, means to move 35 said table horizontally, a grinding drum, means to feed said drum vertically in the direction of a grinding cut, a pattern associated with said machine, and automatic means controlled by said pattern and effective to advance or withdraw said 40 stone horizontally relative to said drum as said drum is fed vertically downward.

4. A stone finishing machine having, in combination, a work supporting table, means to move 45 said table horizontally, a grinding drum, means to feed said drum vertically in the direction of a

grinding cut, means to present loose abrasive for gravity feed to said drum, a pattern mounted in said machine, and automatic means controlled by said pattern effective to cause said drum and stone to horizontally approach or recede with respect to each other as said drum is fed vertically downward.

5. In a stone finishing machine, a grinding drum, means to feed said drum vertically in the direction of the grinding cut, a work supporting table, a reversible motor to move said table horizontally toward or away from said grinding drum, a pattern bar mounted on said table, a roll engaging said bar, a supporting arm for said roll mounted for vertical movement with said drum, and contact devices at both sides of said arm and movable vertically therewith, said devices being selectively engageable by said arm when said roll is displaced from normal angular position by said bar during relative vertical movement between said roll and bar, and said contacts controlling said reversing motor.

6. In a stone finishing machine, a fixed pattern support, a flexible pattern member, and means to secure said pattern member to said fixed support at a plurality of spaced points and in a selected configuration, said latter means comprising a plurality of slotted bars pivotally connected at spaced points to said flexible pattern member, and securing devices mounted in said fixed support and extending through the slots in said bars.

7. A stone finishing machine having, in combination, a work supporting table, means to move said table horizontally, a grinding drum, means to feed said drum vertically, means to feed loose abrasive to said drum, a motor for said grinding drum, a bearing structure for said grinding drum and motor, a grinding carriage on which said bearing structure is horizontally slidably, an eccentric, means to drive said eccentric, a link having an opening at one end for said eccentric, and a stud on said carriage on which the other end of said link is pivoted.
